CLAIM

The ornamental design for a combined back applicator and container therefor, as shown and described.

DESCRIPTION

FIG. 1 is a exploded front elevational view of the combined back applicator and container therefor showing my new design;

FIG. 2 is an assembled front elevational view shown on an enlarged scale;

FIG. 3 is a left side elevational view thereof;

FIG. 4 is a right side elevational view thereof;

FIG. 5 is a top plan view thereof; shown on an enlarged scale;

FIG. 6 is a bottom plan view thereof; and,

FIG. 7 is an isometric view thereof.

The applicator tip, partially disclosed in FIG. 1 is cylindrical and unornamented, with planar top and bottom surfaces.
